DEVICE FOR ACCOMMODATING WOUND
FILM BANDS

Werner Scupin, Namslau, Germany

Application May 10, 1934, Serial No. 724,969
In Germany January 21, 1933

2 Claims. (Cl. 242—72)

This invention relates to a device with which a wound film band can be gripped without touching the edges of the outer layer of the band and be removed from the film holder.

5 The feature of the invention consists in that the device is composed of a central axle carrying radially adjustable elements which can be introduced into the space surrounded by the innermost film band layer and then pressed against 10 this band layer; owing to the adjustability of the lengths of the arms the drive can be introduced into small or large band rolls.

An embodiment of the invention is illustrated 15 diagrammatically by way of example in the accompanying drawing in which:—

Fig. 1 is a plan view of the inner side of the disc on which the device is supported.

Fig. 2 shows the inner side of the cover disc.

Fig. 3 is a vertical section through Fig. 4.

20 Fig. 4 is a section on line IV—IV of Fig. 3.
Three plates 1 forming the bottom of the device are interconnected by an outer ring 2 which is interrupted at three points by windows 3; these windows 3 and windows 4 situated between the 25 plates 1 serve for looking into the interior of the device. The plates 1 are placed on a tube 5 through which a tube 7 extends which is supported by means of blocks 6. An adjusting disc 8 is arranged rotatable about the tube 7 and secured by a ring 25 fixed on the tube 7. This adjusting disc 8 has teeth on one face, these teeth engaging with pinions 9 keyed each on the end of one screw spindle 10. These spindles 10 extend through apertures in the tube 5 and their other 30 ends rotate in bearings 11 in the ring 2. Spindle tubes 12 surrounding the spindles 10 and secured against rotation carry each a block 13 on which a rubber pad 14 is fixed.

35 If the adjusting disc 8 is rotated in one direction, the rubber pads 14 move radially outwards from the centre, that is from the tube 7, whereas they move towards this tube if the adjusting disc

5 is rotated in the opposite direction. To insert the pad aggregate into the space formed by the inner layer of a wound film band 24, the pads must be in the last mentioned position, whereupon by rotating the adjusting disc 8 the buffers 15 are pushed against the innermost film band layer, which is thus firmly held. In order to secure the disc 8 against backward rotation, it has notches 16 in its rim with which a locking pin 18 engages under the pressure exerted by a spring 17. The 10 pin 16 can be disengaged from the notch by means of a knob 19. It is evident that the shape 15 of the locking pin and of the notches can be so chosen that the pin easily engages in the notches and is pressed back out of engagement by the rotating disc 8. A cover disc 19 with windows 20 and with an outer ring 22 having windows 21 has a screw threaded tube 23 which is screwed on to the end of the tube 7, so that the film roll is enclosed between the discs 1 and 19.

20 I claim:—

1. A device for accommodating wound film bands to be inserted in the space in the rolled film, comprising in combination a hollow axle, a plurality of screw threaded spindles extending 25 radially from said axle, pinions one on the inner end of each of said spindles, blocks mounted one on each of said spindles, secured against rotation but shiftable in the longitudinal direction of said spindles, a toothed adjusting disc engaging all of 30 said pinions and rotatable on said hollow axle to rotate said spindles through the intermediary of said pinions to radially displace said blocks relatively to said axle, and rubber pads one on the outer side of each of said blocks adapted to bear 35 against the innermost layer of the wound spool.

2. In a device as specified in claim 1 the adjusting disc provided with notches and at least one locking pin adapted to engage said notches to secure said disc against accidental rotation.

WERNER SCUPIN.
